UNITED STATES PATENT OFFICE

168,198

SEWING MACHINE

Chauncey E. Waltman and Ned L. Wallenberg,
Chicago, Ill., assignors to Union Special Ma-
chine Company, Chicago, Ill., a corporation of
Illinois

Application September 18, 1951, Serial No. 16,671

Term of patent 14 years

(Cl. D70—1)

To all whom it may concern:

Be it known that we, Chauncey E. Waltman and Ned L. Wallenberg, citizens of the United States and residents, respectively, of Chicago, county of Cook, State of Illinois, have invented a new, original, and ornamental Design for a Sewing Machine, of which the following is a specification, reference being had to the accompanying drawing, forming a part hereof, in which:

Figure 1 is a front elevational view of a sewing machine showing our new design.

Figure 2 is a top plan view of said sewing machine.

Figure 3 is an end elevational view of said sewing machine as seen from the left in Figure 1.

Figure 4 is an end elevational view of said sewing machine as seen from the right in Figure 1.

Figure 5 is a rear elevational view of said sewing machine.

We claim:

The ornamental design for a sewing machine,
as shown.

CHAUNCEY E. WALTMAN.
NED L. WALLENBERG.
